UNITED STATES PATENT OFFICE.

HENRY F. PARKER, OF NEW YORK, N. Y., ASSIGNOR TO A. H. ANDREWS & CO.

DESIGN FOR AN END SUPPORT FOR SEATS.

SPECIFICATION forming part of Design No. 16,816, dated July 20, 1886.

Application filed June 17, 1886. Serial No. 205,492. Term of patent 7 years.

To all whom it may concern:

Be it known that I, HENRY F. PARKER, a citizen of the United States, residing at New York city, in the county and State of New York, have invented and produced a new and original Design for the End Supports of Seats or Benches, of which the following is a specification, reference being had to the accompanying drawing, forming part thereof.

10 The drawing, consisting of one figure, represents in elevation the design of my seat and support.

15 Heretofore seat end supports have had the general contour or outline as is shown in the drawing, with the exception, perhaps, of the curves *a* and *b*, which I believe to be new. The surface of the seat end inclosed by the outlines or contour, however, has been of a miscellaneous ornamental character, the chief object 20 having been simple ornamentation without regard to its fitness for special purposes.

25 The ornamentations of my seat ends are ecclesiastical in character, and consist, essentially, of the foliation *c* at the upper end of the support, with a series of lilies, *d*, extending down the back, their stem terminating in a rosette, *e*, the opening *f* in form of a trefoil cross, a rosette or flower, *g*, in open-work, the scallops *h*, rosette *k*, inclosing a star, *l*, the

30 serrated opening *m*, terminating at each end into curves *n*, the Egyptian design *o*, the trefoils *p* and *r*, and the curves *a* and *b*, before referred to, at the base of the support, having the foliated ornamentation *s* and *t*.

35 The whole of the ornamentation, when taken together, has a general ecclesiastical appearance well fitting the design, to harmonize with the surroundings of a church or other place of worship.

I claim—

40 The design for a seat end or support herein shown and described, the same consisting of the foliation *c* at the upper end of the support, with a series of lilies, *d*, extending down the back, their stem terminating in a rosette, 45 *e*, the opening *f* in form of a trefoil cross, a rosette or flower, *g*, in open-work, the scallops *h*, rosette *k*, inclosing a star, *l*, the serrated opening *m*, terminating at each end into curves *n*, the Egyptian design *o*, trefoil *p* and *r*, the 50 curves *a* and *b* at the base of the support, and having the foliated ornamentation *s* and *t*, the whole within the outline or contour of the seat end.

HENRY F. PARKER.

In presence of—

HAL BELL,
ALEX. I. MAYER.
